DESIGN FOR A SUIT ENSEMBLE

Jacob A. Silverman, Brooklyn, N. Y.

Application August 15, 1939, Serial No. 86,702

Term of patent 3½ years

To all whom it may concern:

Jacob A. Silverman, a citizen of the United States of America, residing in New York city, in the Borough of Brooklyn, county of Kings, and State of New York, have invented a new, original, and ornamental Design for a Suit Ensemble, of which the following is a specification, reference being had to the accompanying drawing, forming part thereof, wherein:

I claim:

The ornamental design for a suit ensemble, substantially as shown.

JACOB A. SILVERMAN,
